HANDLE STRUCTURE

Original Filed Aug. 6, 1948

UNITED STATES PATENT OFFICE

2,675,101

HANDLE STRUCTURE

Eleanor P. Bartlett, Dover-Foxcroft, Maine

Original application August 6, 1948, Serial No. 42,921. Divided and this application September 8, 1952, Serial No. 308,471

5 Claims. (Cl. 190—57)

1

This invention relates to new and useful improvements in handle structures and more particularly a handle structure disclosed but not claimed in my co-pending application Serial No. 42,921, filed August 6, 1948, now U. S. Patent No. 2,613,950, issued October 14, 1952, of which this application is a division.

The primary object of the present invention is to provide an adjustable handle structure that is quickly and readily clampingly attached to a suitcase so that the suitcase may be handled in a convenient manner.

Another important object of the present invention is to provide a handle structure composed of two slidably connected spring urged members to which pressure members are hingedly attached so that the same may be clampingly engaged with a suitcase.

A further object of the present invention is to provide a handle structure of the aforementioned character wherein the pressure members slidably and adjustably support side members that are hingedly attached to a telescoped hand grip, so that the device is adaptable to suitcases of the like of various depths, and further, wherein the hand grip may be disposed relatively close to or away from the portion of a suitcase on which the handle structure is attached.

A still further aim of the present invention is to provide a handle structure primarily adapted for suitcases and which handle structure is extremely simple and practical in construction, strong and reliable in use, neat and attractive in appearance, light in weight, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, in which:

Figure 1 is a perspective view of a suitcase and showing the present invention applied thereto;

Figure 2 is a longitudinal vertical sectional view taken substantially through the center of the handle structure;

Figure 3 is a transverse vertical sectional view taken substantially on the plane of section line 3—3 of Figure 2;

Figure 4 is a fragmentary, horizontal sectional view taken substantially on the plane of section line 4—4 of Figure 2;

Figure 5 is a longitudinal vertical sectional view taken substantially on the plane of section line 5—5 of Figure 6; and

2

Figure 6 is a fragmentary perspective view of one end portion of the suitcase used in conjunction with the present invention.

Referring now to the drawings in detail, wherein for the purpose of illustration, there is disclosed a preferred embodiment of the present invention, the numeral 10 represents the handle structure generally, including a pair of substantially rectangular inner and outer straps or members 12 and 14.

A plurality of longitudinally spaced guide pins 16 are fixed to the inner section 12 and project outwardly therefrom to slidably engage a longitudinal slot 18 provided in the outer section or strap 14.

In order to normally urge the straps 12 and 14 inwardly relative to each other, there is provided an elongated resilient member or coil spring 20, the ends of which are anchored to holding pins 22, 24 and are fixed to the respective straps 12 and 14.

Suitably secured by adhesive means or the like to the inner face of the strap 12, is a pair of substantially rectangular strips of resilient material 26 having serrated or toothed bearing surfaces 28.

The outer end of the strap 12 is notched and apertured, as at 32, to pivotally engage the reduced arcuate end portions 34 of a side member or section 36 and the outer end of the strap 14 is also apertured, as at 40, to pivotally engage the reduced arcuate end 42 of a further side member or section 44.

Fixed to the inner faces of the side sections 36 and 44, by rivets or the like 46, are holding plates 48 to which there are fixed resilient pads 50 preferably formed with toothed or serrated bearing surfaces 52. These rivets 46 are provided with substantially rectangular head portions 54 that slidably engage longitudinal slots 56 provided in a pair of side elements or straps 58.

Further, guide pins 60 are also fixed to the side sections 36 and 44 and engage the slots 56 to permit only longitudinal movement of the straps relative to the side sections 36 and 44.

Threaded studs integral with the heads of guides 54 receivably engage wing nuts 62 which are adjustably to bear against the straps 58 in order to adjustably retain the straps 58 in a selected extended position relative to the side sections 36 and 44.

An auxiliary, substantially channel-shaped guide 64 is fixed to the side section 36 and slidably receives and supports the strap 58 during longitudinal movement thereof relative to said side section 36.

A pair of slidably engaged concavo-convexed

hand gripping sections 66 and 68 are provided with reduced arcuate or looped outer terminals 70 that engage notches 72 in the upper ends of the straps 58 and openings or apertures 74 adjacent the upper ends of the straps 58 for pivotal movement of the straps 58 relative to the hand grips 66 and 68.

To prevent disengagement of the hand grips 66 and 68 from each other, there is provided a pair of detents or lugs 76 which are integral with one of the grips and which bear against the remaining grip.

A transverse bar 78 is fixed by welding or the like to the central portion of the inner section 12, between the pads or strips 26, and includes outwardly projecting terminal hooks 80 that will engage headed bolts or fasteners 82 that are removably carried by one end wall 84 of a suitcase or baggage 86.

In practical use of the present invention, the side sections 36 and 44 of the handle structure 10 are pulled outwardly away from each other and placed on opposite sides of the suitcase 86. The spring 20 will urge the said side sections 36 and 44 inwardly to bear against the outer faces of the suitcase 86, and the terminal hooks 80 will engage with the fasteners 82 to prevent movement of the handle structure 10 relative to the suitcase. The wing nuts 62 are tightened when the grips 66 and 68 are disposed at a selected extended position relative to the straps 12 and 14.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A handle structure for suitcases and the like, said handle structure comprising a pair of slidably connected straps, means urging said straps inwardly toward each other, bearing members hinged to said straps, a hand grip, side members carried by said hand grip, means carried by said bearing members slidably engaging said side members, and means adjustably securing said side members to said bearing members, said hand grip including a pair of slidably connected sections.

2. A handle structure comprising a pair of slidably connected juxtapositioned rigid straps each having an outer end, a pair of arms hinged to the outer ends of said straps, spring means connect-

ing and urging the outer ends of said straps toward each other, a pair of elongated side members having lower portions overlapping said arms, means slidably and adjustably securing the side members to the arms, and a hand grip including a pair of slidably connected sections having outer ends attached to the upper ends of said side members.

3. A handle structure comprising a pair of slidably connected juxtapositioned rigid straps each having an outer end, a pair of arms hinged to the outer ends of said straps, spring means connecting and urging the outer ends of said straps toward each other, a pair of elongated side members having lower portions overlapping said arms, means slidably and adjustably securing the side members to the arms, and a hand grip including a pair of slidably connected sections having outer ends attached to the upper ends of said side members, and a resilient pressure pad secured to the inner face of each of said arms.

4. A handle structure comprising a pair of slidably connected juxtapositioned rigid straps each having an outer end, a pair of arms hinged to the outer ends of said straps, spring means connecting and urging the outer ends of said straps toward each other, a pair of elongated side members having lower portions overlapping said arms, means slidably and adjustably securing the side members to the arms, and a hand grip including a pair of slidably connected sections having outer ends attached to the upper ends of said side members, said spring means comprising a coil spring overlying and paralleling said straps and terminally attached to the outer ends of said straps.

5. A handle structure comprising a pair of slidably connected juxtapositioned rigid straps each having an outer end, a pair of arms hinged to the outer ends of said straps, spring means connecting and urging the outer ends of said straps toward each other, a pair of elongated side members having lower portions overlapping said arms, means slidably and adjustably securing the side members to the arms, and a hand grip including a pair of slidably connected sections having outer ends attached to the upper ends of said side members, a transverse bar fixed to one of said straps and having terminal hooks projecting laterally from said one of said straps and adapted to engage headed fasteners secured to one wall of a suitcase.
